Louis Greenberg
by Eugene Lewin, Atty.

UNITED STATES PATENT OFFICE.

LOUIS GREENBERG, OF INDIANAPOLIS, INDIANA.

WASHING-MACHINE.

1,330,801.

Specification of Letters Patent. Patented Feb. 17, 1920.

Application filed September 22, 1919. Serial No. 325,387.

To all whom it may concern:

Be it known that I, LOUIS GREENBERG, a citizen of the United States, residing at Indianapolis, in the county of Marion and

5 State of Indiana, have invented new and useful Improvements in Washing-Machines, of which the following is a specification.

This invention relates to a device which may be used as a washing machine and consists in the matters hereinafter described and more particularly pointed out in the appended claims.

In the accompanying drawings—

Figure 1 is a vertical sectional view of a 15 device, constructed in accordance with my invention;

Fig. 2 is a sectional view taken through the container on line 2—2 of Fig. 1;

Fig. 3 is a horizontal sectional view taken 20 on line 3—3 of Fig. 2;

Figs. 4 and 5 are vertical sectional views taken on lines 4—4 and 5—5, respectively, of Figs. 1 and 2; and

Fig. 6 is a diagrammatic view to be hereinafter referred to in detail.

As shown in the drawings, the device of my invention comprises a base member 1, preferably made flat and circular and having an upturned marginal flange 2, from 30 which are bent portions 3 to provide feet for supporting the device above the floor or other underlying support. Extending upward from the center of the base member 1 is a post 4, cylindrical in shape and having 35 its lower portion screwed into an upright, tubular boss 5 with which the base member is provided. The lower threaded end of said post 4 extends beneath the base member 1 and receives a clamp nut 6 for locking 40 the post against turning and endwise displacement. The upper end of said post 4 is reduced and extends above a housing 7 secured to the marginal flange 2, by fastening members 8. Said post 4 has its upper end 45 bifurcated to provide a vertical slot 9 therein, with the upright side portions 10, 10 thereof laterally spaced apart to receive a rectangular block 11 pivoted between said side portions by a pin 12. Surrounding said 50 post 4 is a sleeve or rotative member 13 having its upper end projecting above the housing 7 and there provided with an outwardly extending, annular flange 14, made flat and arranged at an inclination to the vertical 55 axis of rotation of said sleeve. All portions of said flange 14 are in said inclined plane.

Located above said flange 14 is a plate 15 made flat and circular and preferably having a diameter greater than said flange 14 and arranged concentric therewith. Said plate 15 is inclined to the same extent as said flange and is tiltably connected with the upper end of the post 4 in the following manner. The plate is provided, adjacent its center, with two downwardly extending ears 16, 16, preferably formed by being bent out of the body of the plate, as shown in Fig. 4. The ears 16 are alike and are laterally spaced apart to receive therebetween the block 11 which is connected with said ears by pivot members 17, 17. The upper end of the sleeve 13 opens through the flange 14 from beneath, to permit the ears 16, 16 to extend into the same and engage the post 4. The pivot member 17, 17 are in direct alinement 70 and are at right-angles to the pivot pin 12, thus permitting the plate 15 to be tilted with respect to the post 4 in intersecting vertical planes at right-angles to each other. Interposed between the flange 14 and the plate 75 15 are a plurality of rollers 18, 18, permitting the flange to be rotated easily beneath the plate. As shown, said rollers are carried by the flange 14 and are arranged with their tread or rolling surfaces projecting 80 above the flange and in rolling contact with the under side of the plate 15, the latter thus in effect resting on said rollers. Three rollers 18 are employed, as shown in dotted lines in Fig. 2, and are spaced apart circumferentially equal distances, so that the plate will properly engage the flange 14. In the construction shown, the rollers 18 are 85 located in vertical slots provided in the flange 14 adjacent its outer edge and each 90 roller is held in position by a fastening screw 19 extended through the roller and the outer edge of the flange.

Removably mounted on the plate 15 is a 95 container or receptacle 20 preferably made of metal and circular in shape, and concentric with said plate. Said container has an upright outer wall 21, a flat bottom wall 22, and a top wall 23 having an opening centrally arranged and closed by a removable 100 cover 24, provided with a handle 25 on the outside thereof. The container is also provided with handles 26, 26, secured to the upright wall 21 on the outside thereof to facilitate lifting and handling of said container. 105 The container is provided with a plurality of internal ribs 27, 28, the former on the

side wall 21 and extending between the top and bottom walls, and the latter on the bottom wall 22.

For rotating the sleeve or rotatably mounted member 13, I provide a worm gear 29 secured by screws 30 to the lower end of said sleeve, there being an antifriction bearing 31 interposed between said gear wheel and the upper end of the part 5. Located in the housing 7 is a motor 32, the armature shaft of which is horizontally arranged and provided with a worm 33 in mesh with the worm gear 29.

The container is detachably connected with the plate 15, so that it may be removed completely from the mechanism to facilitate the filling and emptying of the same and also for cleaning purposes. As shown, the plate 15 is provided at its outer margin with two circumferentially spaced ears 34, 34, integral with the plate and bent upwardly and inwardly to engage over an outwardly projecting, annular flange 35 at the bottom of the container. The plate 15 is also provided on its outer margin with a lug 36 integral with and bent upward from the plate to receive a set screw 37, the inner end of which engages over said flange 35, as shown in Figs. 1 and 2. By withdrawing the screw 37 from its engagement with the flange 35, the container 20 may be readily and easily removed from the plate 15.

The device shown and described, operates as follows: When used as a washing machine, the articles of clothing or other fabrics to be washed, are placed in the container, together with the required amount of water and soap or other washing ingredient, and the cover 24 is applied to close the container. The latter is then placed on and secured to the plate 15, or the container may be first applied to the plate and then filled. The motor 32 is then started by turning on the current, and as the motor operates the rotating member or sleeve 13 and its flange 14 are rotated in one direction, while the post 4 and its connected container 20 are not revolved in a horizontal plane. As the inclined flange 14 rotates beneath the container, the latter is tilted up and down in intersecting vertical planes at right-angles to each other and passing through the axis of rotation of said flange 14 during each revolution of the latter, thereby agitating the water in the container and effecting a washing of the fabric articles.

In order that the type of motion imparted to the container may be more fully understood, let it be assumed that the parts occupy the positions shown in full lines in Figs. 1 and 6, when the motor is started. As the inclined flange 14 is revolved, the lowermost point *a* on its outer edge is carried around in a horizontal plane *b*, which is below the point *c* of pivotal connection be-

tween the post 4 and the container. The highest point *d* of said flange 14 is carried around in a horizontal plane *e* parallel with the plane *b* and above the pivotal point *c*. Thus, when the flange 14 has been revolved 180° from the starting point mentioned, said flange is in the position shown by the dot and dash lines *g* in Fig. 6. As the point *a* moves toward the right, from its position shown in full lines in Fig. 6, the container tilts on the pins 17 toward the plane *b*, and when the point *a* reaches a position 90° from its starting point, the container has been tilted into the position shown by the dotted lines *o* in Fig. 6. When the point *a* reaches a point diametrically opposite its full line position, the container tilts on the pin 12 to the position shown by said dot and dash lines *g*. When the point *a* reaches a position 270° from the starting point mentioned, the container tilts again on the pins 17 and occupies a position shown by the dotted lines *r* in Fig. 1. When the point *a* has made a complete revolution, it is brought back to its starting point. The container tilts gradually as the inclined flange 14 revolves, and progresses from one tilted position to another in the rotation of said flange. In each complete revolution of the latter, the point *h* on the lower edge of the container is moved up and down in the arc *i* of a circle, the center of which is the pivotal point *c*, while the point *j* on the opposite side of the container is moved up and down in the arc *k* of the same circle. In tilting, the lower edge of the container progresses about a circle in a horizontal plane of the line *f*, and the container is not rotated bodily about a vertical axis. The line *m* in Fig. 6 passes through the center of the container and the pivotal point *c* when the container is in the tilted position shown in full lines; the line *n* passes through said point *c* and the center of the container when the latter is in the tilted position shown by dotted lines *o*; and the line *p* passes through said point *c* and the center of the container when the latter has been tilted to the position shown by the dot and dash lines *g*. The upper and lower lines *f*, *g*, define the extreme distance that the container is tilted.

A device made as described, is compact, as all of the operative parts are below the container, and the weight being below the container, the device is prevented from upsetting as the container is tilted. By providing the container with ribs 27, 28 and tilting the container progressively as the flange 14 revolves, sufficient agitation is given to the water and articles in the container to make the washing thorough and rapid.

While I have shown and described in detail a device embodying the features of my invention, it is to be of course understood that the details of construction and arrangement

of parts shown may be variously changed and modified without departing from the spirit and scope of my invention, and further that the device described may be used for purposes other than washing clothes and other fabric articles.

I claim as my invention:

1. A washing machine, comprising a tiltably mounted container, an annular member 10 rotatably mounted below said container and arranged at an inclination to the axis of rotation of said member and acting on said container upon the rotation of said member to effect the tilting of said container, and 15 means for rotating said annular member.
  2. A device of the character described, comprising a tiltably mounted container, an inclined annular member rotatably mounted below said container and acting when rotated to tilt said container and cause the lower edge thereof to be progressed around in a plane intersecting the plane of inclination of said annular member, and means for rotating said annular member.
  3. A washing machine, comprising a tiltably mounted container adapted to receive the articles to be washed, and mechanism located below said container and including a rotatably mounted annular member 20 arranged at an inclination to the axis of rotation of said annular member to effect the tilting of said container upon the rotation of said annular member, said container having detachable connection with said mechanism so that the container may be removed therefrom.
  4. A washing machine, comprising an upright post, a container tiltably connected with said post, a sleeve surrounding said post and being provided with means acting on said container upon the rotation of said sleeve to effect the tilting of said container, and means for rotating said sleeve.
  5. A washing machine, comprising an upright post, two members, one being a container tiltably connected with said post and the other rotatably engaged therewith, said members acting upon the rotation of one of the same to effect the tilting of the tiltably mounted member.
  6. A washing machine, comprising an upright post, a container tiltably connected
- with said post, a sleeve surrounding said post and provided with an annular flange arranged at an inclination to the axis of rotation of said sleeve and acting to effect the tilting of said container upon the rotation of said sleeve, and means for rotating said sleeve.
7. A device of the character described, comprising a stationary upright post, a plate tiltably connected with said post, a container mounted on said plate and having detachable connection therewith, a sleeve surrounding said post and having an annular flange below said plate and arranged at an inclination to the axis of rotation of said sleeve, rollers interposed between said plate and flange, and means for rotating said sleeve.
8. A device of the character described, comprising a stationary upright post, a plate tiltably connected with said post, a sleeve surrounding said post and having an annular flange below said plate and arranged at an inclination to the axis of rotation of said sleeve, rollers interposed between said plate and flange, and means for rotating said sleeve.
9. A device of the character described, comprising a stationary upright post having its upper end slotted, a block in said slot and pivotally connected with the sides thereof, a plate above said post and secured to the block by a pivotal connection arranged transverse to the pivotal connection of said block with said post, a sleeve surrounding said post and having an annular flange below said plate and arranged at an inclination to the axis of rotation of said sleeve, rollers interposed between said plate and flange, and means for rotating said flange.
10. As an article of manufacture, a sleeve having an annular flange having all portions thereof arranged in a plane inclined to the longitudinal axis of said sleeve and provided with rollers projecting above said flange.
- In testimony that I claim the foregoing as my invention, I affix my signature, this 19th day of September, A. D. 1919.

LOUIS GREENBERG.
